UNITED STATES PATENT OFFICE

1,968,776

ELECTRIC HEATER

Ralph F. Schneider, St. Clair Shores, Mich.

Application October 16, 1933, Serial No. 693,839

3 Claims. (Cl. 219—38)

This invention relates to electric heaters, and particularly to electric heaters of the mono-unit type.

The principal object of the present invention is to provide an electric mono-unit heater constructed of concrete or the like, as contradistinguished from electric mono-unit heaters made of metal or the like.

Other objects of the invention will be readily apparent to those skilled in the art upon reference to the following detailed description of an embodiment of the invention, shown in the appended drawing whose

Fig. 1 is an elevational section view of the embodiment as if on line 1—1 of Fig. 2; and whose

Fig. 2 is a right end view of the embodiment.

Referring to the drawing, it will be seen that the embodiment there disclosed comprises a concrete radiator and heater body 10 generally in the form of a prism, the body having a hollow interior 11 lined with a sheet metal box 12, preferably of galvanized iron. The body is formed with grooves 14 of inverted U shape which provide radiating ribs 15 on the two vertical sides 20 and on the horizontal top of the body, the bases 25 of the grooves being spaced far enough away from the lining 12 so as to leave a shell of concrete all around the lining.

Passed through aligned apertures in an end wall of the body 10 and in an end wall of the lining 12 and embedded in the wall of the body 10 is a supporting pipe 16 on the exposed threaded end of which is an internally threaded cap 17 upon which is mounted a multi-station switch 18 provided with a switch knob or button 19. The switch is mounted on the exposed end of a small bore tube 20 which passes into the box 12 through a hole in the cap 17, and which is surrounded by heating coils 21. It is preferred to have the coils 21 so wound and interconnected that the multi-station switch 18 will apply loads of 1000 watts, 500 watts, 250 watts, or 0 watts, depending upon the position given to the knob 19 by the operator, in accordance with well known practice in electrical heater construction.

The tube 16 is sealed at its exposed end by the cap 17 and accordingly the hollow interior 11 remains sealed from the outside of the radiator, despite the presence of the electrical heater.

It will also be observed that the cap plate 17 and the electrical heating element carried thereby, including parts 18—21, are removable as a unit from the threaded exposed end of the embedded tube 16 and accordingly removal and re-

placement of the heater for any purpose whatever can readily and easily be effected.

Passing through the body 10, from end to end thereof, and through the lining 12, and the sealed hollow space 11, are hollow tubes 26 whose open ends are provided with control valves 27 of the rotatable shutter type. These tubes and their shutters are provided to permit a circulation of air through the tubes 26 in sealed relation, to the sealed space 11, so that, when desired, a room 60 may be heated quickly by opening the shutters 27 and permitting the air passing through the tubes 26 to be heated by the heated air in the sealed space 11.

Passing through the body 10 from end to end 70 thereof, but above the lining 12, are tubes 28 having on their open ends shutter control valves 29, and these tubes also permit the circulation of air through the radiator, whenever desired, to enhance the heating action of the radiator, the 75 circulating air in these tubes being heated by the heated concrete of the body.

Inasmuch as the radiator is made of concrete, it is desirable to reinforce the same and accordingly reinforcing means are provided. Among 80 such means are the tie rods 31, passing through the body from end to end, above the lining 12 and the tubes 28, and tie rods 32 passing through the body from end to end below the lining 12, the tie rods having on their ends, heads and nuts 85 to maintain them in place, the heads and nuts being embedded in the end walls of the body so as to lie flush with the surface thereof.

There are also provided vertical reinforcing rods 34 having their lower ends embedded in the 90 legs 35 at the corners of the body, the rods passing upwardly near the opposite ends of the lining 12.

There is also provided for the radiator a transverse rib 36 whose contour is similar to that of 95 the legs 35 and this transverse rib, aids in supporting the unsupported span of the body, from one pair of legs 35 to the other. Passing upwardly from the rib 36 and into the body of the radiator are a plurality of vertical tie rods or 100 bolts 38 and these have their lower ends embedded in the rib 36 and their upper ends terminating short of the lining 12.

The various reinforcing rods or bolts 34 and 38 have on their ends heads and nuts, in accordance with proper practice.

The foregoing described embodiment has proven efficient and satisfactory in all essentials. The radiator described can be built at far less cost than heaters of equivalent performance and 110

is superior to known heaters in many respects.

Inasmuch as there is no body of water contained in the radiator, or circulating through the radiator, problems of freezing, water sealing, packing, plumbing, etc., are eliminated. Similarly inasmuch as there is no circulation of the air in the radiator, apart from what circulates through the straight through tubes 26 and 28, there is no possibility of dust collecting in inaccessible portions of the radiator, as is the case with certain types of circulating air heaters. Further, inasmuch as the radiator is made of concrete or a like material, the radiator, when once heated, will retain its heat for a considerable length of time, after the current has been turned off.

Other advantages and features will readily be apparent to those well acquainted with electrical heating problems and the manufacture of electrical heaters, and will not here be enumerated for purposes of brevity.

Now having described a preferred embodiment, which embodiment is disclosed by way of compliance with the statutes made and provided in such cases, and which disclosure is not intended as limiting the invention to the specific details of construction here disclosed, reference will be had to the appended claims for determination of the scope of the invention.

30 I claim:

1. An electrical heater of the class described comprising a hollow concrete radiator whose hollow interior is sealed from the outside of the radiator, an electrical heater passing through an end wall of said radiator and into the sealed hollow space thereof and having an exteriorly projecting portion provided with a control for the heating unit of the heater, a sheet metal lining for the sealed hollow space, a tube passing through opposite end walls of said radiator, lining, and space and having open ends whereby air

may circulate therethrough, the tube being sealed from the space and valves on the ends of the tube the sides and top of the radiator being grooved to provide radiating pins therebetween.

2. An electrical heater of the class described comprising a hollow concrete radiator whose hollow interior is sealed from the outside of the radiator an electrical heater passing through an end wall of said radiator and into the sealed hollow space thereof and having an exteriorly projecting portion provided with a control for the heating unit of the heater, a sheet metal lining for the sealed hollow space, a tube passing through opposite end walls of said radiator, lining, and space and having open ends whereby air may circulate therethrough, the tube being sealed from the space, and valves on the ends of the tube, and a second tube passing through opposite end walls of said radiator, remote from said lining and space and also having open ends the side and top of the radiator being grooved to provide radiating pins therebetween.

3. An electrical heater of the class described comprising a hollow concrete radiator whose hollow interior is sealed from the outside of the radiator, an electrical heater passing through an end wall of said radiator and into the sealed hollow space thereof and having an exteriorly projecting portion provided with a control for the heating unit of the heater, a sheet metal lining for the sealed hollow space, a tube passing through opposite end walls of said radiator, lining, and space and having open ends whereby air may circulate therethrough, the tube being sealed from the space, and valves on the ends of the tube, and a second tube passing through opposite end walls of said radiator, remote from said lining and space and also having valve controlled open ends the sides and top of the radiator being grooved to provide radiating pins therebetween.
